UNITED STATES PATENT OFFICE.

OTTO NENTWIG, OF NEUSTADT, GERMANY.

BOX OF BUILDING MATERIAL.

SPECIFICATION forming part of Letters Patent No. 707,446, dated August 19, 1902.

Application filed September 5, 1901. Serial No. 74,447. (No model.)

To all whom it may concern:

Be it known that I, OTTO NENTWIG, a subject of the Emperor of Germany, residing at Neustadt, in the Province of Silesia, Germany, have 5 invented new and useful Improvements in Toy Building-Blocks, of which the following is a specification.

My invention relates to toy building-blocks, and more especially to such with which a complete building having floors and roofs, doors, windows, &c., may be formed.

Heretofore building-blocks were made for the enjoyment and instruction of children, who placed such blocks upon each other to 15 form various structures or figures. The disadvantage with such blocks, even when used in connection with bars in toy structures or figures, is that the latter are liable to fall apart, and making it impossible to move the 20 toy building after being put together.

The object of my invention is to provide blocks which are interlocking, so that when the toy building is put together it may be removed from place to place without danger of 25 its falling apart. In connection with the blocks use is made of T, I, or L bars, which serve to connect such structures properly and to form trusses, girders, &c., and, further, suitable provisions are made on the said bars 30 to hold my improved blocks in their relative positions.

My invention will be more fully understood taken in connection with the accompanying drawings, forming part hereof, and in which—

35 Figure 1 illustrates a part of a toy building composed of my improved building blocks and bars and having imitation doors and windows. Fig. 2 shows a door to be used in connection with the said blocks. Fig. 3 is a vertical section through the said door. Fig. 4 is 40 a horizontal section through the same. Fig. 5 is an elevation of one of my improved building-blocks. Fig. 6 is a horizontal section through the same. Fig. 7 is a vertical section through the same. Fig. 8 is an elevation 45 of a corner-block. Fig. 9 is a top view of the corner-block shown in Fig. 8. Fig. 10 shows the footing of a corner-block. Fig. 11 is a plan thereof. Fig. 12 is an elevation of a 50 building block or bar adapted to clamp or hold other blocks together. Fig. 13 is an end

view thereof. Fig. 14 is an elevation of a T-shaped bar. Fig. 15 is an end view thereof. Fig. 16 illustrates the construction of a gable-roof. Fig. 17 shows the construction of an 55 arched roof. Fig. 18 shows a hip-roof. Fig. 19 illustrates a block especially adapted for the construction of a roof. Fig. 20 is a longitudinal section thereof. Fig. 21 is a transverse section thereof. Fig. 22 shows a block 60 adapted to form the hip and rafter of the roof. Fig. 23 illustrates in elevation a roof-covering block. Fig. 24 is a side view thereof. Fig. 25 illustrates another form of roof-covering block. Fig. 26 is a side elevation thereof. 65

Referring now to the drawings for a further description of my invention, and especially to Fig. 1, it will be seen that the improved blocks for toy buildings are of different shapes to form corners, panels, doors, and windows, 70 &c., and may be of any desired material, such as wood or stone, or they may be made of sheet metal pressed into the desired shape, as shown, for instance, in Figs. 5 and 7. These blocks *a* are generally plate-like, and 75 two or more of their edges are provided with grooves *b* and tongues *c*. The tongues and grooves are not arranged on the same edges of all the blocks, many blocks having tongues or grooves only on one or two of its edges. 80 The arrangement of these grooves and tongues is optional and should be such that in every case when the blocks are put together to form a wall, floor, roof, or other structure the connections of the several blocks with each other 85 will be interlocking, as shown, for instance, in Fig. 1.

In Figs. 8 to 11 are shown corner-blocks, which are also made of sheet metal, forming tongues *k*, adapted to be engaged by the 90 grooves *b* of the flanges *o* of the building-block. *m* is a splice-plate fitting inside the grooves formed by the tongues *k* for the purpose of holding the corner-blocks vertically 95 in position. The footing *n* of the corner-block is made by bending the lower portions outwardly, as shown at *o* in Fig. 11.

Similarly to the blocks *a* I provide the doors and windows with grooves and tongues. The door shown in Figs. 2, 3, and 4 is made 100 of two sheets of metal *f* and *g*, which have formed thereon panels, &c. These two sheets

are held together on three edges by lap-joints forming tongues *d*, and the lower edges are bent outwardly, as shown at *j*, and a T-shaped strip *e* is inserted between these two sheets 5 and bent around the projections *j* to form lap-joints *h* and *i* to hold the sheets together at the bottom.

To hold the top courses of blocks *a* together, T-shaped strips *l*, Figs. 14 and 15, fitting the 10 grooves *b* of the blocks *a*, are provided and applied as shown in Fig. 1, the joints of the blocks *a* being broken with the joints of the strips *l*, and to provide a flat and wide surface on top of the walls so formed and to 15 further stiffen the top course of blocks *a* and strips *l* channeled bars, as shown in Figs. 12 and 13, are slid over the strips *l*, and the joints of these strips *l* are broken with the joints of the channeled bars. These channeled bars 20 or clamping-strips are also adapted to fit over the tongues *c* of the blocks *a* should they be turned as to present the said tongue uppermost. In such case, however, the T-shaped strips *l* are dispensed with.

25 On top of the clamping-strips just described and holding the upper courses of blocks in position may be placed the roof, which may be a gable-roof, as shown in Fig. 16, in which the ridge is formed of corner-blocks, as shown in Figs. 8 and 9, and supported by rafters consisting of special strips or blocks. The roof-covering may consist of blocks *a*, as shown on either side of Fig. 16, or of special roof-covering plates *r*, as shown 30 in the center of Fig. 16 and detailed in Figs. 19 to 21. These roof-covering plates *r* are made of any material, but preferably of perforated sheet metal with bent edges *t*. The perforations in these plates *r* are so designed 35 that shingles *u*, provided with hooks, as shown in Figs. 23 to 26, may be applied to the plates *r*.

In Fig. 17 is shown the assembling of building-blocks to form an arched roof, and this 40 may be accomplished by the use of T-bars, as shown in Figs. 14 and 15, and the clamping-strips, as shown in Figs. 12 and 13. The

covering in this case consists of the blocks *a*, as shown in Figs. 5, 6, and 7.

The plates *r* (shown in Figs. 16 and 19 to 50 21) may also be used in connection with plates *s*, as shown in Figs. 18 and 20, to form a hip-roof, and the several plates *r* and *s* are held together by clamping-strips (shown in Figs. 12 and 13) and engaging the bent edges 55 *t* of the plates *r* and *s*.

Having thus described the nature and objects of my invention, what I claim as new, and desire to secure by Letters Patent, is—

1. Toy building-blocks representing wall- 60 surfaces, doors, windows, and roof-covering having tongues and grooves on their respective edges, in combination with T-shaped strips, whose stem or tongue portion is adapted to fit the grooves of the said blocks and 65 hold them in line, substantially as and for the purposes set forth.

2. Toy building-blocks representing wall-surfaces, doors, windows, and roof-covering having tongues and grooves, in combination 70 with T-shaped strips, whose stem or tongue portion is adapted to fit the grooves of the said blocks and hold them in line, of channeled bars adapted to slide over the flange portion of the T-shaped strip and rigidly tie 75 the same together, substantially as and for the purposes set forth.

3. Toy building-blocks representing wall-surfaces, doors, windows, and roof-coverings having tongues and grooves, in combination 80 with corner-blocks provided with hollow tongues adapted to fit the grooves of the said building-blocks and hold them in line vertically, and splice-plates fitting the said hollow tongues of the corner-blocks, substantially 85 as and for the purposes set forth.

In testimony whereof I have signed my name to this specification in the presence of two subscribing witnesses.

OTTO NENTWIG.
